TOE REST FOR SHOE MACHINES

Sidney J. Finn, Beverly, Mass., assignor to United Shoe Machinery Corporation, Flemington, N. J., a corporation of New Jersey

Application November 19, 1940, Serial No. 366,263

13 Claims. (CL 12—123)

This invention relates to shoe machinery, and particularly to a work rest or support for engaging the forepart of a lasted shoe during the application of pressure to the shoe bottom.

In machines for applying pressure to the bottoms of lasted shoes, the shoe is ordinarily held, during pressure application, by supporting means engaging the cone of the last and the forepart of the shoe in the vicinity of its toe portion. The supporting means for engaging the forepart, or toe rest as it is commonly called, is usually in the form of a resilient yieldable pad, shaped to conform substantially to the rounded contour of the toe portions of shoes, and suitably mounted so as to provide adequate support against the pressure. The center of support of such a toe rest is approximately over a line extending lengthwise of the shoe, from the center of the heel end of the shoe bottom to the extreme forward end or point of its toe portion, hereinafter called the longitudinal center line of the shoe bottom; whereas the areas of the shoe bottom on either side of its longitudinal center line are, in most shoes at least, unequal, the outside area being the larger. Stated another way, the center of support of the toe rest is not directly over a line, passing through the center of the heel end of the shoe bottom and also through the center of gravity of the shoe bottom area against which pressure is applied, about which the moments of the shoe bottom areas on each side thereof are equal, hereinafter referred to as the longitudinal moment axis of the shoe bottom area, but, instead, is offset inwardly therefrom, widthwise of the shoe, a distance varying with the shape of the last.

As a result of this unbalanced condition, where the pressure is applied to the shoe bottom by means which are incapable of equalizing the pressure, such as the flexible ironing plates employed in the machine for applying heat and pressure to shoe bottoms disclosed in United States Letters Patent No. 2,095,245, granted on October 12, 1937, on an application of S. J. Finn, there will not be an even distribution of pressure over the bottom of the shoe. Where pressure is applied by means capable of equalizing the pressure on the shoe bottom, such as a yielding pad of the type used in the machine for cement-attaching soles to shoes disclosed in U. S. Letters Patent No. 2,047,185, granted July 14, 1936, on an application of Ballard et al., there is a tendency for the shoe to rock or turn and to sink unequally into the yielding pad during pressure application. In each case the operation of the machine is

adversely affected and the quality of the work may be seriously impaired.

It is an object of this invention, therefore, to provide an improved toe rest for conformably engaging the rounded toe portion of a lasted shoe which is capable of supporting a shoe during the application of pressure to its bottom in such a way as to assure uniformity of pressure throughout the entire area of the shoe bottom and to eliminate all tendency of the shoe to rock or sink unevenly into a yielding pressure-applying pad. With this end in view, there is provided, as an important feature of this invention, a toe rest having a pad shaped to conform substantially to the rounded toe portions of shoes, together with supporting means therefor comprising a member arranged for movement, laterally of the toe rest and independently of the pad, to locate the effective center of support of the pad, and hence of the toe rest, to one side of the longitudinal center line of the shoe bottom and substantially over the longitudinal moment axis of the area of the shoe bottom to which pressure is to be applied. In order to accommodate variations in the shapes of different lasts, the supporting member is arranged, in accordance with a further feature of the invention, so as to be readily adjustable laterally of the toe rest, thus permitting a selective positioning of the effective center of support of the toe rest widthwise of a shoe in accordance with the particular type of shoe being handled.

Preferably, and as herein illustrated, the improved toe rest has a resilient yielding pad comprising two portions shaped for conformably engaging the rounded toe portion of a lasted shoe, one on each side of the longitudinal center line of the shoe bottom, and proportioned in size substantially to the relative sizes of the inside and outside areas of a shoe bottom on each side of its longitudinal center line. The pad portions are mounted on separate pressure-transmitting means which in turn are supported on a pressure-distributing member bearing against a shiftable fulcrum block carried by the body of the toe rest. The arrangement is such that the total supporting effect of the toe rest is so distributed between the two pad portions that the fulcrum block forms the effective center of support of the pad, and also of the toe rest. By shifting the fulcrum block laterally, which may be done without moving the pad, a greater portion of the pressure will be applied through, or sustained by, one of the pad portions and the effective center of support of the toe rest thus offset laterally from

the longitudinal center line of the shoe bottom, and located substantially above the longitudinal moment axis of the area of the bottom of the shoe supported by the toe rest. In this way, balanced conditions are obtained and operation of the machine and quality of the work greatly improved.

While the improved toe rest is especially adapted for use in the kind of shoe machines referred to above and in which the application of pressure to the shoe bottom is a primary function, it will be appreciated that it is also suitable for use in other kinds of shoe machines in which the application of pressure to the shoe bottom is incidental to, or combined with, other operations, such as, for example, that performed by lasting instrumentalities. In the latter case, as in the former, uniformity of pressure application is assured and the operation of the machine correspondingly improved.

These and other features and objects of the invention will appear more fully from the following description when read in connection with the accompanying drawing and will be pointed out in the appended claims.

In the drawing,

Fig. 1 is a view in side elevation of a portion of a machine for applying pressure to the bottoms of shoes and having a toe rest embodying the features of this invention;

Fig. 2 is a rear elevation, partly in section, of the toe rest shown in Fig. 1; and

Fig. 3 is a view looking up at the bottom of the toe rest shown in Fig. 1 with the pad cover removed.

The illustrated toe rest, indicated generally by the reference character 10 in Fig. 1, is shown mounted on a rocking member 12 which forms a part of the pressure-applying mechanism of a machine for pressing the bottoms of shoes such as is disclosed in the above-mentioned patent to Finn. See especially Fig. 15 of that patent. In the operation of this machine the lasted shoe S is supported against upward movement by means of the toe rest 10 and a heel support 14, also mounted on the rocking member, to hold it against pressure imposed on the bottom of the shoe by flexible ironing plates, one of which is represented at P in Fig. 1, in a manner fully explained in said patent. The toe rest comprises a supporting leg 20 formed at its upper end with a T-slot 22 which slidably engages a T-guide 16, formed on one end of the rocking member 12. A spring-actuated locking plunger 24 is arranged selectively to engage any one of several locating grooves 26 in the guide 16 for holding the toe rest in adjusted position lengthwise of the rocking member. Below the T-slot 22, and on the back face of the supporting leg, are vertically spaced horizontal machined surfaces 28 and 30 forming a transverse groove which is covered by a sheet metal casing 32 secured in place by screws 34. Extending upwardly through the lower part of the supporting leg are spaced bores 36 and a central bore 38.

A stud 40 projecting from a hollow head member 42 is received within the bore 38 and secured therein by means of a set screw 44. Slidably mounted in the spaced bores 36 are plungers 46 and 48 having rounded upper ends 50, 50. At their lower ends these plungers are enlarged to provide flat heads 52, 52 generally triangular in shape, see Fig. 3. The hollow head 42 is open at the bottom and is provided with side walls 54, 54, a rear wall 56 and a central rib 58. The

heads 52, 52 of the plungers 46 and 48 fit somewhat loosely in the triangular spaces formed by these side walls and the central web. Positioned in the head below the plungers is a pad 60, formed of rubber or like resilient material and provided at opposite edges with sheet metal reinforcing members 62. These reinforcing members are interposed between the bottom of the pad and the heads 52 of the plungers and also between the sides of the pad and the walls 54 and 56 of the hollow head 42. The pad 60 is traversed by a deep groove 61 which divides it into two portions, one on each side of the central web 58 of the head 42.

A flexible cover 66, made of leather, fabric or similar material, is secured to the head by means of anchor screws 68 so as to hold the pad from falling out of the head and about in the position shown in Fig. 2. The rounded ends 50, 50 of the two plungers 46 and 48 bear against a rocking bar or pressure-distributing member 70 which, when a shoe is pressed against the toe rest, is backed up by a fulcrum block 72 slidably mounted on the surface 28 of the supporting leg 20 and having a rounded fulcrum surface 74. The fulcrum block is adjustable laterally of the toe rest by means of a screw 76 threaded into the block and journaled in the casing member 32. A turning knob 78 holds the screw against movement in one direction while a spring 80 bearing against a washer 82 fixed on a projecting end of the screw yieldingly resists movement in the opposite direction.

In the operation of the machine, the shoe S is placed upon the plates P, beneath the toe rest 10 and the heel-end support 14, and its toe end shifted widthwise so as to be generally centered with respect to the pad 60, which is shaped at 86 to conform generally with the rounded contour of the toe part of a shoe. As pressure is applied to the bottom of the shoe, by upward movement of the plates P, the pressure of the toe rest, against the toe portion of the shoe, is transmitted to the two portions of the pad 60, from the fulcrum block 72 and the pressure-distributing member 70, by plungers 46 and 48. The fulcrum block thus forms the effective center of support of the pad 60, and also of the toe rest, and its position, with respect to the two plungers, determines the proportionate part of the pressure which will be sustained by or applied through each pad portion.

In Fig. 1 a right shoe is shown, and its larger outside ball area will be beneath the right-hand pad portion, as viewed in Fig. 2. By positioning the fulcrum block 72 nearer to the right-hand plunger 46 a greater part of the pressure will be sustained by or applied through the right-hand pad portion and the effective center of support of the pad and toe rest, provided by the fulcrum block, will be shifted widthwise of the shoe and to the right in Fig. 2. With the block 72 appropriately positioned the effective center of support can be brought substantially over the longitudinal moment axis of the shoe bottom area, and, with the center of support thus located, conditions will be balanced so that the pressure applied by the pressure-applying means will be uniformly distributed over the entire area of the shoe bottom. Likewise, if the shoe were being forced into a yielding pressure pad by means of the toe rest, as, for example, in a machine such as that shown in the above-mentioned patent to Ballard et al., the forces acting on the shoe would be balanced so as to elim-

inate any tendency of the shoe to rock or to sink unevenly into the yielding pad.

The appropriate position of the fulcrum block 72 for suitably locating the effective center of support of the toe rest will, of course, vary with different shoes, and necessary adjustment of the block can be readily made by turning the knob 78. To facilitate the setting of the block, appropriate indicia, indicated at 88, are provided on the casing 32 to cooperate with a line 90 formed on a pin 92 carried by the block and extending through a slot 94 in the casing. Inasmuch as a toe rest for supporting a left shoe is the same as that shown in the drawing, except that an oppositely shaped head and pad are provided, these indicia are extended on each side of the center of the toe rest, it being appreciated that the fulcrum block would have to be shifted to the left, as viewed in Fig. 2, to bring the effective center of support of the pad over the longitudinal moment axis of the bottom area of a left shoe.

In order substantially to equalize the pressure intensity on the upper materials, thus to avoid concentration of pressure at one point which might damage the upper materials, the pad 60 is unsymmetrical in shape, see Fig. 3, the right-hand pad portion, Fig. 2, having a larger area contacting the shoe than does the left-hand pad portion. Since the relative magnitudes of the pressures applied through or sustained by the two pad portions, when the fulcrum block is positioned properly to locate the effective center of support of the pad widthwise of a shoe, will be approximately in the ratio of the relative sizes of the outside and inside areas of a shoe bottom on each side of its longitudinal center line, the pad portions are proportioned in size, approximately, to these areas, as illustrated in Fig. 3.

Having described the invention, what I claim as new and desire to secure by Letters Patent of the United States is:

1. A toe rest for shoe machines comprising a body, a pad for conformably engaging the forepart of a lasted shoe to hold the shoe during the application of pressure to its bottom, and means for supporting the pad on the body, said means including a member constructed and arranged for movement relatively to the body and independently of the pad to locate the effective center of support of the toe rest to one side of the longitudinal center line of the shoe bottom.

2. A toe rest for shoe machines comprising a body, a pad for conformably engaging the forepart of a lasted shoe to hold the shoe during the application of pressure to the shoe bottom, and means for supporting the pad on the body, including a member constructed and arranged for movement laterally of the toe rest, said member being adjustable relatively to the body and independently of the pad to vary the position of the effective center of support of the toe rest with respect to the longitudinal center line of the shoe bottom.

3. A toe rest for shoe machines comprising a body, a pad for conformably engaging the forepart of a lasted shoe to hold the shoe during the application of pressure to the bottom of the shoe, and means for supporting the pad on the body, said means including a member constructed and arranged for movement relatively to the body and independently of the pad to locate the effective center of support of the toe rest substantially over the longitudinal moment axis of the area of the shoe bottom to which pressure is applied.

4. A toe rest for shoe machines comprising a body, a pad for conformably engaging the forepart of a lasted shoe to hold the shoe during application of pressure to the shoe bottom, and means for supporting the pad on the body, said means including a member shiftable laterally of the toe rest and independently of the pad to change the position of the effective center of support of the toe rest with respect to the longitudinal center line of the shoe bottom.

5. A toe rest for shoe machines comprising a body, a pad having portions for conformably engaging the forepart of a lasted shoe on opposite sides of the longitudinal center line of the shoe bottom to hold the shoe during pressure application to its bottom, and means for supporting the pad portions on the body, said means being interposed between the body and the pad portions and including members constructed and arranged to distribute the pressure between the pad portions in such a manner that the effective center of support of the toe rest is offset laterally from the longitudinal center line of the shoe bottom.

6. A toe rest for shoe machines comprising a body, a pad having portions for conformably engaging the forepart of a lasted shoe on opposite sides of the longitudinal center line of the shoe bottom to hold the shoe during the application of pressure to its bottom, pressure-transmitting means associated with each pad portion, and means, bearing against the body and the pressure-transmitting means, constructed and arranged to distribute pressure between said pressure-transmitting means, and their associated pad portions, in such a manner that the effective center of support of the toe rest is substantially over the longitudinal moment axis of the area of the shoe bottom.

7. A toe rest for shoe machines comprising a body, a pad mounted on the body and having portions for conformably engaging the forepart of a lasted shoe on opposite sides of the longitudinal center line of the shoe bottom to hold the shoe during application of pressure to its bottom, pressure-transmitting means associated with each pad portion and movably carried by said body, and means for applying a greater pressure to one of said pressure-transmitting means than to the other thereby to shift the effective center of support of the toe rest widthwise of the shoe.

8. A toe rest for shoe machines comprising a body, a pad mounted in the body and having portions for conformably engaging the forepart of a lasted shoe on opposite sides of the longitudinal center line of the shoe bottom to hold the shoe during the application of pressure to its bottom, plungers slidably mounted in the body each having enlarged portions at one end bearing on each of said pad portions, a pressure-distributing member engaging the opposite ends of said plungers, and means for transmitting a pressure from the body to said distributing member.

9. A toe rest for shoe machines comprising a body, a pad mounted in the body and having portions for conformably engaging the forepart of a lasted shoe on opposite sides of the longitudinal center line of the shoe bottom to hold the shoe during the application of pressure to its bottom, plungers slidably mounted in the body and having at one end enlarged heads bearing on said pad portions, a pressure-distributing member engaging the opposite ends of said plungers, and means for transmitting a pressure from the body to the plungers through said distributing mem-

ber, said pressure-transmitting means being shiftable laterally of the body to vary the position of the effective center of support of the toe rest with respect to the longitudinal center line of the shoe bottom.

10. A toe rest for shoe machines comprising a body, a pad mounted on the body and having portions for conformably engaging the forepart of a lasted shoe on opposite sides of the longitudinal center line of the shoe bottom to hold the shoe during the application of pressure to its bottom, plungers slidably mounted in the body and having enlarged heads at one end bearing on the said pad portions, a pressure-distributing member comprising a bar engaging the opposite ends of said plungers, and a fulcrum block adjustably supported in the body and bearing on the bar for transmitting pressure from the body to the plungers.

11. A toe rest for shoe machines comprising a body, a hollow open-sided head secured to the body, a pad received in said head and having portions for conformably engaging the forepart of a lasted shoe on opposite sides of the longitudinal center line of the shoe bottom to hold the shoe during the application of pressure to its bottom, plungers slidably mounted in the body and extending at one end into said head and into engagement with the pad portions, a pressure-distributing member engaging the opposite ends of the plungers, a fulcrum block supported on the body and bearing on the bar between said plungers for transmitting pressure from the body to the pad portions, and means for adjusting the block laterally of the body to vary the position of application of pressure to the bar and thereby to shift the effective center of support

of the pad laterally of the toe rest and widthwise of the shoe.

12. A toe rest for shoe machines comprising a body, a hollow open-sided head on the body, a pad received in said head and extending from its open side including portions for conformably engaging the forepart of a lasted shoe on opposite sides of the longitudinal center line of the shoe bottom to hold the shoe during the application of pressure to its bottom, one of said pad portions having a substantially larger contact area than the other pad portion, plungers slidably mounted in the body and extending at one end into said head to engage the pad portions, a pressure-distributing bar engaging the opposite ends of the plungers, a fulcrum block supported on the body and bearing on the bar between said plungers for transmitting pressure from the body to the pad portions, and means for adjusting the block laterally of the body to vary the point of application of pressure to the bar and thereby to shift the effective center of support of the pad widthwise with respect to the center line of the shoe bottom and toward the pad of larger contact area.

13. A toe rest for shoe machines comprising a body, a pad mounted on the body and having portions for conformably engaging the forepart of a lasted shoe on opposite sides of the longitudinal center line of the shoe bottom to support the shoe, pressure-transmitting means associated with each pad portion and movably carried by said body, and means for applying a greater pressure to one of said pressure-transmitting means than to the other thereby to shift the effective center of support of the toe rest widthwise of the shoe.

SIDNEY J. FINN.
